UNITED STATES PATENT OFFICE

130,025

DESIGN FOR AN ADVERTISING FIGURE

Andrew J. Kilgariff, Pittsburgh, Pa.

Application August 4, 1940, Serial No. 94,233

Term of patent 7 years

To all whom it may concern:

Be it known that I, Andrew J. Kilgariff, a citizen of the United States, residing at Pittsburgh, in the county of Allegheny and State of Pennsylvania, have invented a new, original, and ornamental Design for Advertising Figures, of which the following is a specification, reference being had to the accompanying drawing, forming part thereof.

I claim:

The ornamental design for an advertising figure, as shown.

ANDREW J. KILGARIFF.
